(57) **CLAIM**

The ornamental design for a child's outerwear garment, as shown and described.

DESCRIPTION

FIG. 1 is a front view of a child's outerwear garment, according to a first embodiment, where the front panel is in an opened state and the shoulder flaps are in a disengaged state.

FIG. 2 is a rear view of the child's outerwear garment illustrated in FIG. 1.

FIG. 3 is a rear view of the child's outerwear garment illustrated in FIG. 1 where the front panel is in a closed state and the shoulder flaps are in an engaged state.

FIG. 4 is a top view of the child's outerwear garment illustrated in FIG. 1 where the front panel is in the closed state and the shoulder flaps are in the disengaged state.

FIG. 5 is a rear view of the child's outerwear garment illustrated in FIG. 4.

FIG. 6 is a top view of the child's outerwear garment illustrated in FIG. 3.

FIG. 7 is a front view of the child's outerwear garment illustrated in FIG. 3.

FIG. 8 is a left side view of the child's outerwear garment illustrated in FIG. 3.

FIG. 9 is a left side view of the child's outerwear garment illustrated in FIG. 4.

FIG. 10 is an enlargement of region 10 in FIG. 1.

FIG. 11 is an enlargement of region 11 in FIG. 1.

FIG. 12 is an enlargement of region 12 in FIG. 2.

FIG. 13 is an enlargement of region 13 in FIG. 2.

FIG. 14 is an enlargement of region 14 in FIG. 3.

FIG. 15 is an enlargement of region 15 in FIG. 4.

FIG. 16 is an enlargement of region 16 in FIG. 5.

FIG. 17 is an enlargement of region 17 in FIG. 6.

FIG. 18 is an enlargement of region 18 in FIG. 7.

FIG. 19 is an enlargement of region 19 in FIG. 8.

FIG. 20 is an enlargement of region 20 in FIG. 9.

FIG. 21 is an enlargement of a front view of a child's outerwear garment, according to a second embodiment, where the front panel is in a closed state and the shoulder flaps are in a disengaged state; and,

FIG. 22 is an enlargement of a top view of the child's outerwear garment illustrated in FIG. 21.

The short dashed broken lines in the figures showing an outerwear garment represent the environment of the design and form no part of the claim. The dashed-dotted lines in the

(Continued)

figures are for illustration purposes only and form no part of the claim. The reference numbers and lead lines in FIGS. 1-9 that touch the dashed-dotted lines are for illustration purposes only. The reference numbers in FIGS. 1-9 refer to the figure in which an enlargement of the region defined by the dashed-dotted lines is illustrated.
